UNITED STATES PATENT OFFICE.

JACOB BARGER, OF LACEYVILLE, AND JOHN SAMUEL HILTON, OF DEERSVILLE, OHIO.

MACHINE-BRAKE.

SPECIFICATION forming part of Letters Patent No. 360,080, dated March 29, 1887.

Application filed December 6, 1886. Serial No. 220,830. (No model.)

To all whom it may concern:

Be it known that we, JACOB BARGER and JOHN SAMUEL HILTON, citizens of the United States, residing, respectively, at Laceyville 5 and Deersville, in the county of Harrison and State of Ohio, have invented certain new and useful Improvements in Machine-Brakes; and we do declare the following to be a full, clear, and exact description of the invention, such 10 as will enable others skilled in the art to which it appertains to make and use the same, reference being had to the accompanying drawings, and to the letters and figures of reference marked thereon, which form a part of this 15 specification.

This invention relates to motors, and is principally designed for running light machinery, such as churns, &c.

The object of the invention is to devise a 20 compact arrangement of the parts, whereby a simple and economical device is produced, combining therewith efficiency and durability in use.

The improvement consists in the novel features hereinafter described and claimed, and 25 more fully shown in the annexed drawings, in which—

Figure 1 is a perspective view of a motor provided with our improvements. Fig. 2 is a 30 plan view of the brake-lever and roller.

The frame of the motor comprises the four corner posts, A, the upper and lower side rails, A' A², and the upper and lower end rails, A³ A⁴. The parallel bars B are arranged between 35 the end bars A³ at a point midway between the side rails A', and a short cross-bar, B', is arranged between one of them and the side rail A', as shown. The windlass-arbor C is journaled in brackets between one of the bars 40 B and the side rails A', and has its outer end extended beyond said side rails and provided with a gear-wheel, e, keyed thereto.

The drum or windlass D, keyed to the shaft, is connected by a ratchet and pawl in the usual 45 manner with a gear-wheel, D', loosely mounted upon said shaft and meshing with a pinion, e, upon a shaft, e', mounted in bearings secured to the short cross-bar B' and the bar B. The power-transmitting shaft F, mounted in suitable 50 bearings to the right of the parallel bars,

has a pinion, f, on its inner end, which meshes with a gear-wheel, E, keyed upon the shaft e'. The outer end is provided with a crank, f', which is connected by the link f² with the horizontally-arranged lever G.

The lever G extends longitudinally with the frame, and is pivoted to one of the corner posts, and held close against the other by the keeper g. The rear end is notched on its upper side and receives a weight, g', which may be 55 adjusted nearer to or farther from the pivot or fulcrum, to counterbalance the weight of the connections attached to the front end, which end is adapted to communicate motion to the desired machine by means of a suitable rod, 60 as g².

The brake-lever H, pivoted to the side of one of the bars B, has an offset, h, formed therein, beyond which it is extended, and is connected to the end bar of the frame by the coil-spring h'. The friction-roller I, mounted upon the return-arm h² of the offset, is adapted 70 to be thrust against the power-transmitting shaft F and check the movement of the same, when so desired.

The motor may be run by either spring or weight power, as desired, the latter being preferred, in which case the rope or chain will be attached at one end to the windlass and passed over a pulley or sheave on the tower or derrick J, and be provided with a suitable weight, K, at its other end.

Having thus described our invention, what we claim, and desire to secure by Letters Patent, is—

The brake-lever H, having the offset h and the return-arm h², and having its end extended beyond the return-arm, the roller I, mounted upon the return-arm h², and the spring h', interposed between the frame and the extended 80 end of the lever, said brake adapted for operation with a train of gearing, substantially as and for the purpose described.

In testimony whereof we affix our signatures in presence of two witnesses.

JACOB BARGER.

JOHN SAMUEL HILTON.
